Inventor,

Fannie B. Cutler

UNITED STATES PATENT OFFICE.

FANNIE B. CUTLER, OF RONALD TOWNSHIP, IONIA COUNTY, MICHIGAN.

MONKEY-WRENCH.

972,342.

Specification of Letters Patent. Patented Oct. 11, 1910.

Application filed March 10, 1909. Serial No. 482,633.

To all whom it may concern:

Be it known that I, FANNIE B. CUTLER, a citizen of the United States, residing in the township of Ronald, county of Ionia, 5 and State of Michigan, have invented new and useful Improvements in Monkey-Wrenches, of which the following is a specification.

My invention relates to monkey wrenches, 10 and its object is to secure a wrench of simple construction, which may be operated as quickly, easily and efficiently as possible.

As hereinafter more fully described, it 15 consists of a wrench having two parallel bars between the handle and the fixed head, a dog catch fastened between the two bars by a specially constructed pivot, a movable head sliding on the bars, and an aperture in which a finger may be inserted to assist in 20 adjusting the jaws about the object to be engaged. It also has a strong spiral spring between the handle and the movable jaw, which is inclosed in two cylinders, the lower part of the spring being in the cylinder 25 which is attached to the handle, and the upper part in a larger cylinder which is fastened to the jaw, and which slides down over the lower one when the jaws are drawn apart. The upper cylinder has teeth on the 30 side toward the bars, which are engaged by teeth on the dog catch when it is placed in position.

In the following detailed description reference is had to the accompanying drawings, 35 in which—

Figure 1 is a view of the wrench with the jaws closed and the dog turned so that its teeth are engaged with the teeth on the cylinder. Fig. 2 is a longitudinal section. Figs. 40 3, 4 and 5 are cross sections on the lines 3—3, 4—4, and 5—5, respectively, in Figs. 1 and 2.

Between the handle and ferrule G and the fixed head and upper jaw, shown in Figs. 1 and 2, are two parallel bars F, side views of 45 which are given in Figs. 1 and 2, and a cross section in Fig. 5. The dog catch D, best shown in Fig. 2, has teeth on the free end which engage with the teeth on the upper cylinder A when turned in the right position 50 by the pivot E, which is rotatably mounted in the bars and provided with an intermediate square portion on which is mounted the

dog D. The movable jaw of the wrench, shown in Figs. 1 and 2, envelops the two parallel bars as shown in Fig. 5. There is 55 also an aperture C in the movable jaw of the wrench. Between the ferrule and the movable jaw of the wrench there is a strong spiral spring H, a portion of which is shown in Fig. 2. The spring is sheathed in two 60 cylinders A and B, as shown in Figs. 1 and 2. On the side of the upper cylinder are teeth which engage with the teeth on the dog catch, as shown in the drawings, and before described. 65

In operating the wrench, a finger is placed in the aperture in the movable jaw, pulling it away from the fixed jaw until the jaws can be placed about the object to be engaged thereby. Then the movable jaw is released, 70 the spring pressing it against the object to be engaged. In case the spring is not strong enough for the work, the dog is turned to engage the teeth on the cylinder. When the object is to be released the operation is reversed, the dog being turned back between the bars where it is kept when not in use, and the movable jaw pulled back by the finger in the aperture. 75

I claim as my invention, and desire to 80 secure by Letters Patent of the United States:—

1. As an improvement in wrenches, the combination of a fixed head a handle and parallel bars connecting the same, a toothed 85 dog catch pivoted between the bars, a sliding jaw on said bars provided with an aperture, a strong spiral spring between the handle and movable jaw, normally forcing the latter toward the fixed jaw, two hollow 90 cylinders incasing the spring, the smaller attached to the handle and the larger to the movable jaw, the larger cylinder having teeth on the side toward the bars, to be engaged by the teeth on the dog catch, as set 95 forth.

2. As an improvement in wrenches, the combination of a fixed head a handle and parallel bars connecting the same, a dog provided with teeth on the free end pivoted between the bars, the dog being rotatable to engage and disengage its teeth, with teeth on a cylinder carried by a sliding jaw on said bars, said sliding jaw provided with an 100

aperture, a strong spiral spring between the handle and the movable jaw, normally forcing the latter toward the fixed jaw, two hollow cylinders incasing the spring, the 5 smaller attached to the handle and the larger to the movable jaw, the larger cylinder having teeth on the side toward the bars, to be engaged by the teeth on the catch, as set forth.

FANNIE B. CUTLER.
